(57) **CLAIM**

The ornamental design for a paddle switch with externally facing electrical connector port or ports, as shown and described.

DESCRIPTION

FIG. 1 is a front environmental view of a first embodiment of a paddle switch with externally facing electrical connector ports (i.e., USB ports) showing my design;

FIG. 2 is a side perspective view thereof;

FIG. 3 is a front view thereof;

FIG. 4 is a side view thereof;

FIG. 5 is an opposing side view thereof;

FIG. 6 is an end view thereof;

FIG. 7 is an opposing end view thereof;

FIG. 8 is a front environmental view of a second embodiment of a paddle switch with externally facing electrical connector ports (i.e., USB ports) showing my design;

FIG. 9 is a side perspective view thereof;

FIG. 10 is a front view thereof;

FIG. 11 is a side view thereof;

FIG. 12 is an opposing side view thereof;

FIG. 13 is an end view thereof;

FIG. 14 is an opposing end view thereof;

FIG. 15 is a front environmental view of a third embodiment of a paddle switch with externally facing electrical connector ports (i.e., USB ports) showing my design;

FIG. 16 is a side perspective view thereof;

FIG. 17 is a front view thereof;

FIG. 18 is a side view thereof;

FIG. 19 is an opposing side view thereof;

FIG. 20 is an end view thereof;

FIG. 21 is an opposing end view thereof;

FIG. 22 is a front environmental view of a forth embodiment of a paddle switch with externally facing electrical connector ports (i.e., USB ports) showing my design;

FIG. 23 is a side perspective view thereof;

FIG. 24 is a front view thereof;

FIG. 25 is a side view thereof;

FIG. 26 is an opposing side view thereof;

(Continued)

FIG. 27 is an end view thereof;
 FIG. 28 is an opposing end view thereof;
 FIG. 29 is a front environmental view of a fifth embodiment of a paddle switch with an externally facing electrical connector port (i.e., USB port) showing my design;
 FIG. 30 is a side perspective view thereof;
 FIG. 31 is a front view thereof;
 FIG. 32 is a side view thereof;
 FIG. 33 is an opposing side view thereof;
 FIG. 34 is an end view thereof; and,
 FIG. 35 is an opposing end view thereof
 The broken lines shown herein are for illustrative purposes only and form no part of the claimed design.
